Primary Examiner — Terry A Wallace(74) *Attorney, Agent, or Firm* — Donald Paul Day**CLAIM**

The ornamental design for a full face helmet shaped cooler, as shown and described.

DESCRIPTION

FIG. 1 is a right side perspective view of a full face helmet shaped cooler showing my new design, the opposite side being a mirror image.

FIG. 2 is a right side view thereof, the opposite side being a mirror image.

FIG. 3 is a front view thereof.

FIG. 4 is a rear view thereof.

FIG. 5 is a top plan view thereof.

FIG. 6 is a front perspective view thereof with the lid open; and,

FIG. 7 is a right side view thereof with the handle in a retracted position, the opposite side being a mirror image.
